BOAT OAR

Robert A. Nichols, 613 3rd St. SW.,
Faribault, Minn. 55021

Filed Dec. 3, 1968, Ser. No. 14,775

Term of patent 14 years

Int. Cl. D12—14

U.S. Cl. D71—1

FIG. 1 is a top plan view of a boat oar embodying my design;

FIG. 2 is a side view thereof;

FIG. 3 is a partial longitudinal section taken substantially along line 3—3 of FIG. 1; and,

FIG. 4 is a transverse section taken substantially along line 4—4 of FIG. 1.

I claim:

The ornamental design for a boat oar, substantially as shown.
